UNITED STATES PATENT OFFICE.

HENRY G. HOGG, OF BUFFALO, NEW YORK.

DESIGN FOR A PUZZLE-BOARD.

SPECIFICATION forming part of Design No. 34,641, dated June 11, 1901.

Application filed May 15, 1901. Serial No. 60,409. Term of patent 3½ years.

To all whom it may concern:

Be it known that I, HENRY G. HOGG, a subject of the King of Great Britain, residing at Buffalo, in the county of Erie and State of New York, have invented and produced a new and original Design for a Puzzle-Board, of which the following is a full, clear, and exact description.

The leading feature of my design is a puzzle-board, substantially as shown in the accompanying drawings and set forth herein.

Figure 1 is a perspective view of a puzzle-board, showing my new design. Fig. 2 is a central section through the body portion thereof.

The design consists of a body portion which is circular in contour and which consists of a convex bottom and an upwardly-flaring rim, which extends therefrom and is formed integrally therewith, said rim having a circumferential groove formed on its inner side near its upper end. Branching from the rim of the body portion and integral therewith is an outwardly and upwardly directed handle, at the end of which a head of a buffalo is represented. Arranged transversely in the center of the convex bottom of the body portion are three concaved indentations or pockets.

Referring to the drawings by letters, A designates the convex bottom of the circular body portion. B designates the upwardly-projecting rim of the same. 30

C designates the circumferential groove formed on the interior of the rim near its upper edge.

D designates the outwardly and upwardly 35 directed handle.

E designates the buffalo-head at the end of the handle.

F designates the concaved indentations or 40 pockets in the convex bottom of the body portion.

Having thus described my invention, what I claim as new, and desire to secure by Letters Patent, is—

The design for a puzzle-board, herein shown 45 and described.

In testimony whereof I have hereunto set my hand in the presence of two subscribing witnesses.

HENRY G. HOGG.
